ALFRED HEALD, OF PHILADELPHIA, PENNSYLVANIA, ASSIGNOR TO
McCALLUM, CREASE & SLOAN, OF SAME PLACE.

DESIGN FOR CARPET.

Specification forming part of Design No. 6,715, dated June 24, 1873; application filed June 6, 1873.

To all whom it may concern:

Be it known that I, ALFRED HEALD, of the city and county of Philadelphia, State of Pennsylvania, have invented a Design for a Carpet Pattern, (C,) of which the following is a specification:

The main features of my design, clearly illustrated by the figure in the accompanying drawing, are the members A and B, which are alternated throughout the pattern, as shown.

These members are precisely similar in outline and nearly alike in interior ornamentation; but they present an entirely different appearance, as the members B consist of but a simple outline upon the light groundwork of the carpet, while the members A are of a dark

shade or color, and present, therefore, a much bolder appearance.

The whole of the members A and B are enclosed within borders composed of vines and leaves intertwined and gracefully arranged in the manner clearly shown in the drawing.

Irrespective of the colors employed, I claim—

The design for a carpet-pattern, substantially as described, and as represented in and by the accompanying drawing.

In testimony whereof I have signed my name to this specification in the presence of two subscribing witnesses:

Witnesses: ALFRED HEALD.

HUBERT HOWSON.
